UNITED STATES PATENT OFFICE

96,595

DESIGN FOR AN AUTOMATIC WATER HEATER UNIT

Harvey A. Craig, Pasadena, Calif., assignor to
Rheem Manufacturing Company, Richmond,
Calif., a corporation of California

Application July 2, 1934, Serial No. 52,422

Term of patent 7 years

To all whom it may concern:

Be it known that I, Harvey A. Craig, a citizen of the United States and a resident of Pasadena, and county of Los Angeles, State of California, have invented a new, original, and ornamental Design for an Automatic Water Heater Unit, of which the following is a specification, reference being had to the accompanying drawing, forming part thereof.

Figure 1 is a perspective view of the automatic water heater unit of my invention, as viewed from the front.

Figure 2 is a view similar to Figure 1, showing the automatic water heater unit from the rear.

I claim:

The ornamental design for an automatic water heater unit substantially as shown.

HARVEY A. CRAIG.
